UNITED STATES PATENT OFFICE.

WILLIAM ANDREW BRADY, OF SPENCER, IOWA.

BAND-CUTTER AND FEEDER.

SPECIFICATION forming part of Letters Patent No. 352,112, dated November 9, 1886.

Application filed March 27, 1886. Serial No. 196,832. (No model.)

To all whom it may concern:

Be it known that I, WILLIAM ANDREW BRADY, a citizen of the United States, residing at Spencer, in the county of Clay and State 5 of Iowa, have invented a new and useful Improvement in Band-Cutters and Feeders, of which the following is a specification, reference being had to the accompanying drawings.

My invention relates to an improvement in 10 band-cutters and feeders for thrashing-machines; and it consists in the peculiar construction and combination of devices that will be more fully set forth hereinafter, and particularly pointed out in the claims.

15 In the drawings, Figure 1 is a side elevation of a band-cutter and feeder embodying my invention. Fig. 2 is a vertical longitudinal sectional view of the same. Fig. 3 is a top plan view. Fig. 4 is a vertical transverse sectional 20 view taken on the line $x-x$ of Fig. 2 and looking toward the feed end of the machine.

25 A represents a case, which is adapted to be secured to one end of a thrashing-machine. In the feed end of the said box or case, near the lower side thereof, is journaled a transverse shaft, B, which is provided at its center with a crank, C, and rigidly secured to the said shaft, at one end, is a pair of driving-pulleys, D and E, and loosely secured on the said shaft is a 30 pulley, F, which bears against the outer side of the fixed pulley D.

G represents an inclined feed-board, which forms the bottom of the box or case A, and is located therein and secured thereto by means 35 of bails H, which have their outer ends pivoted to the sides of the box or case and their connecting portions pivoted to the under side of the feed-board G. These bails H form rocking links, which connect the feed-board with 40 the box or case, so that both ends of the feed-board may be simultaneously oscillated up and down in the case. The lower end of the feed-board G, when my attachment is secured to a thrashing-machine, delivers to the thrashing 45 mechanism, and the said feed-board is provided on its upper side with a series of inclined projecting teeth, g, which incline toward the lower end of the feed-board.

K represents a hopper, which is adapted to 50 receive the bundles of grain, and is secured in the feed end of the case A on the upper side

of the feed-board, and is secured to the case A by means of a bail, L, forming rocking links, connecting the said hopper with the case, similarly to the bails connecting the feed-board 55 with the said case. The bottom K' of the hopper is rigidly attached to the upper side of the feed-board by means of pins g', which prevent the bottom of the hopper from coming in contact with the feed-board, although the said 60 bottom of the hopper moves with the feed-board. The sides K² of the hopper merely rest upon the bottom K', but are not secured thereto, and thus the hopper is provided with an independently-movable bottom. The bail L 65 prevents the sides of the hopper from moving lengthwise with the feed-board and the bottom K', but allows the sides to move vertically therewith. From the inner opposing sides of the hopper project the teeth k, and from the 70 bottom board, K', of the hopper project the downwardly-extending upwardly-inclined teeth k'.

L² represents a transverse shaft, which is journaled in the upper sides of the box or case 75 A, immediately in rear of the discharge end of the hopper K and communicating therewith. To the center of this shaft is secured a cutting-wheel, L', the edge of which may be either serrated or sharpened, as will be found most effective. To one end of the shaft L² is secured a pulley, L³, which is connected by an endless belt, M, with the pulley E on the shaft B. To the crank of the said shaft B is attached one end of a pitman, N, the opposite end of which 80 is attached to the under side of the feed-board.

O represents a transverse bar, which is secured on the upper side of the case A in rear of the shaft L², and parallel therewith. Under one end of the bar O is pivoted a horizontal bell-crank lever, P, having a long and a short arm. The long arm of this lever is connected to the bottom of the hopper K and to the feed-board G by means of a rod, R.

S represents a pair of rocking stirring-arms, 95 having their lower ends bifurcated, and thus provided with stirring-fingers S'. The upper ends of the arms S are pivoted to one side of the bar O, and the said arms extend downwardly to within a suitable distance of the upper side of the feed-board, and are connected together by a rod, S', and one of the said 100

arms is connected to the short arm of the bell-crank lever P by means of a rod, S³. An endless belt, T, passes from a suitable driving-pulley on the thrashing-machine (which 5 is not here shown as it forms no part of the present invention) to the pulley D. This endless belt passes through a loop, V', which extends from one side of a belt-shifting lever, V, which is pivoted to one side of the 10 box or case A. By moving this lever the belt may be shifted from the pulley D onto the idle-pulley F when it is desired to throw the band-cutting and feeding mechanism out of gear with the thrashing-machine.

15 The operation of my invention is as follows: When the shaft B is actuated, the feed-board G is caused to simultaneously reciprocate and move upwardly and downwardly by reason of the rocking links H, and, by being connected 20 to the crank C and the bottom of the hopper K, partakes of the motions of the feed-board G, while the sides of the hopper are only free to move vertically. The movement of the feed-board and the hopper causes the bell-crank lever P to work on its pivot, and thereby move or rock the arms S transversely across the upper side of the feed-board. The shaft L² is rotated by being geared to the pulley E, causing the cutting-wheel L' to rapidly rotate in 25 the discharge end of the hopper. The bundle of grain is thrown into said hopper, where it becomes engaged by the teeth k' of the bottom thereof, and on each downward longitudinal movement of the said bottom the bundle is urged toward the wheel L'. On each upward 30 or reverse longitudinal movement of the bottom K' its teeth become disengaged from the bundle, and the latter is caught by the teeth k in the sides of the hopper, and thus prevented from moving away from the cutter L'. From this it will be understood that the action 35 of the hopper and its independently-movable bottom is to constantly move the bundle

upon the wheel L', the edge of which cuts the band, and the loosened straws are fed onto the 45 feed-board and are moved downwardly thereon. As they intersect the paths of the rocking arms S, the fingers of the latter distribute the straws evenly over the face of the feed-board, and they are thereby delivered to the 50 thrashing-cylinder evenly and equally at all points, thus enabling the thrashing-machine to operate with maximum efficiency.

Having thus described my invention, I 55 claim—

1. The combination, in a band-cutter and feeder for thrashing-machines, of the vertically-movable hopper having the independently longitudinally movable bottom, and the 60 rotating cutter located at the discharge end of the hopper, whereby a sheaf thrown into the hopper will have its band presented to the rotating cutter and severed thereby, substantially as described.

2. The combination of the case A, the movable feed-board G, the rocking links connecting the said feed-board to the case, the crank-shaft connected to the feed-board, whereby the latter is caused to move simultaneously back and forth and up and down, and the vertically-movable hopper having the independently-movable bottom K', rigidly attached to the feed-board, substantially as described.

3. The combination of the case A, the movable feed-board G, the hopper, the bail or rocking links L, connecting the hopper to the case, and the independently-movable bottom K' of the hopper attached to and moving with the feed-board, substantially as described.

In testimony that I claim the foregoing as 80 my own I have hereto affixed my signature in presence of two witnesses.

WILLIAM ANDREW BRADY.
